UNITED STATES PATENT OFFICE.

JOHN E. DREW, OF JERSEY CITY, NEW JERSEY, ASSIGNOR TO AMERICAN MACHINE AND FOUNDRY COMPANY, A CORPORATION OF NEW JERSEY.

SICKLE BAR.

Application filed August 26, 1924. Serial No. 734,170.

This invention relates to an improved sickle-bar for harvesting machines, and it has for its main object the production of a device of this character which can be produced at a low cost without sacrificing durability or efficiency. With this and other objects not specifically mentioned in view, the invention consists in certain constructions and combinations which will be hereinafter fully described and then specifically set forth in the claims hereunto appended.

In the accompanying drawings which form a part of this specification and in which like characters of reference indicate the same or like parts, Fig. 1 is a plan view, partly sectional, of a device constructed in accordance with the invention, Fig. 2 is a perspective view showing one of the blades and the locking wedge out of engagement with the reciprocating member, and Fig. 3 is a perspective view showing one of the blades locked in position in said member.

In carrying the invention into effect, there is provided a member having a series of slots provided with oppositely flared walls, a corresponding series of removable blades engaging said walls, and means for locking said blades in said member. These parts may be varied within the scope of the claims, for the particular structure selected to illustrate the invention is but one of a number of possible concrete embodiments of the same. The invention, therefore, is not to be restricted to the precise details of the structure shown and described.

As shown, there is provided a reciprocating member 4 having a series of slots provided with oppositely flared walls 5, one wall of each slot being arcuate in formation and of radii permitting production by milling operations and the other wall being in part arcuate at 6 and in part angular at 7.

Fitting in each slot is a blade 8 having surfaces engaging the walls 5 and 6-7 of the member slots. Each blade also has an angular recess 9 adjacent the angular wall 7 of its slot, and the blade is locked in position in the member by means of a wedge 10 engaging said recess and the angular slot wall

7 as clearly shown in Figs. 1 and 3.

To attach a blade to the member it is in-

serted in its slot, and then the wedge is driven home. To remove a blade, the wedge 10 is withdrawn by means of the engagement of the aperture thereof with a pin wrench not shown. After the wedge has been withdrawn, the blade can be slipped out of the member slot without difficulty.

What is claimed is:

1. A sickle-bar comprising a member having a series of slots provided with two end walls each of which is oppositely flared, a corresponding series of removable blades engaging said walls, and means for locking said blades in said member.

2. A sickle-bar comprising a member having a series of slots provided with two end walls each of which is oppositely flared, a corresponding series of removable blades engaging said walls, and means for locking said blades in said member, one wall of each slot being arcuate in formation and the other wall of each slot being in part arcuate and in part angular in formation, said arcuate walls having centres offset from said sickle-bar.

3. A sickle-bar comprising a member having a series of slots provided with two end walls each of which is oppositely flared, a corresponding series of removable blades engaging said walls, and means for locking said blades in said member, said means including an angular recess formed in each blade and a wedge engaging said recess and one of the slot walls.

4. A sickle-bar comprising a member having a series of slots provided with two end walls each of which is oppositely flared, a corresponding series of removable blades engaging said walls, and means for locking said blades in said member, one wall of each slot being arcuate in formation and the other wall of each slot being in part arcuate and in part angular in formation said arcuate walls having centres offset from said sickle-bar, and said means including an angular recess formed in each blade and a wedge engaging said recess and one of the slot walls.

In testimony whereof, I have signed my name to this specification.

JOHN E. DREW.
